SAFETY RAZOR

Stephen P. Enright, Philadelphia, Pa.

Application April 2, 1937, Serial No. 134,638

12 Claims. (Cl. 30—42)

This invention relates to safety razors and, more particularly, to the kind now commonly known as the "Gillette" type, the cutting stroke of which, in contradistinction to that of a straight razor, may be defined as resembling that of a plane, or a square-cut stroke. This square or straight cutting-stroke is consequent upon the prevailing general construction of such razors, and incidentally shaving with such razors is rarely, if ever, effected without some physical discomfort owing to the "square" cut and attendant pull of the blade.

The primary object of this invention is to overcome the above noted disadvantage by provision of a safety razor in which the blade has imparted thereto, during normal shaving strokes, a to-and-fro or reciprocatory movement; or what may be otherwise defined as a zig-zag movement concurrent with the general direction of the shaving stroke.

A secondary object is to do away with the disadvantage of rigid metal-bound clamping means for securing the razor blade in place and to assure a certain flexibility of said blade, similar to that experienced in the use of a straight razor, and to this end the blade in this invention is clamped between razor head components by employing its own springiness or capacity to recoil when subjected to flexure.

Another object is the provision of a safety razor including a blade reciprocating means having a manipulator member so located, relative to the holder, that the forefinger tip, for example, of the user can be conveniently applied thereto for actuating said blade, with the result that the finger movements automatically follow those of the user's arm without discomfort or fatigue of any kind, other than that incidental to shaving.

A further object is to support the flexible blade for reciprocation with the minimum of frictional resistance.

A still further object is the provision of an efficient guard means for the reciprocatory parts of the safety razor.

Other objects and advantages, more or less ancillary to the foregoing, and the manner in which they are realized in practice, will be apparent from a more complete examination of the following description which, considered in connection with the accompanying drawings, sets forth a practical embodiment of the inventive features.

Generally stated, this invention embraces the novel items, combinations of means, and ar-

rangements of parts hereinafter disclosed, illustrated by the drawings, and more concisely expressed in the claims at the conclusion hereof.

In the drawings:

Fig. I is a longitudinal section through the head portion and part of the holder of a safety razor embodying this invention.

Fig. II is a sectional view, taken approximately as indicated by the arrows II—II in Fig. I.

Fig. III is a similar view on the plane III—III 10 of Fig. I.

Fig. IV is an end view looking toward the right-hand of Fig. I.

Fig. V is a perspective view of the razor blade clamping or locking member.

Fig. VI is a perspective view of the reciprocatory blade carrier.

Fig. VII is a perspective view of the safety razor head; and,

Fig. VIII is a portraiture illustrative of the improved safety razor in use.

Referring generally to the several drawings, the improved safety razor of this invention comprises a holder or handle 1, a base or head 2, a blade carrier 3, the blade 4, a blade clamping or lock member 5, and a shield or guard 6. More specifically, the handle 1 is of conventional form, with the exception that it is provided proximate one end with a housing including spaced walls 7 embodying opposed bearings 8, in which is journaled the axis 9 of a freely-rotative manipulator 10. This manipulator 10 is preferably in the form of a disc rigid with the axis 9, said disc having its peripheral edge milled or serrated at 11 to facilitate its rotation. Concentric with each flat face of the manipulator 10 is an annular cam embodying circumferentially and equally-spaced rises 12; and, it is to be particularly noted the rises 12 of the one annular cam alternate with, or are staggered relative to, those of the other annular cam, for a purpose hereinafter explained.

The head 2 embodies the conventional teeth 13, and an attaching piece or stem 14 for secure fixture in the open end of the handle 1 in accordance with known practice. The head 2 differs, however, in many respects from standard structures of analogous character in that it is, centrally of its outer face, provided with a longitudinal groove 15, a dove-tail guideway 16 defined by spaced projections 17, and an axial orifice 18 through the stem 14, aforesaid. The orifice 18 is somewhat elongate in cross-section, thereby defining spaced walls 14' in which is fulcrumed the axis 19 of a forked rocker 20, the bifurcation 50

55 of a forked rocker 20, the bifurcation 55

extremities whereof are suitably rounded at 21 for antifrictional coaction with the manipulator annular cam rises 12. On the other hand, the leg 22 of the rocker 20 projects beyond the stem axial orifice 18 into a central aperture 23 in the blade carrier 3. Incidentally it is to be remarked that the aperture 23 is reversely coned so that the rocker leg 22 coacts with an angular edge 24 whereby the movement of the carrier 3 is greatly facilitated and friction reduced to the minimum.

The blade carrier 3, as best understood from Figs. I and VI, is of a cross-section for reciprocatory movement and slight lifting action in the head guideway 16, while it is formed with a longitudinal rib 25 for similar engagement in the groove 15, said rib being cut away at 26, Fig. I, to afford free clearance for the rocker leg 22. It is also noteworthy that the head stem 14 is also cut out at 27 to similarly accommodate oscillatory movement of the rocker forked portions 21, as later on set forth. The blade carrier 3 is formed with a central embossment 28 conformative with the customary cut-out in flexible double-edged blades, parallel blade-supporting ribs 29, and longitudinally spaced lock projections 30, the outer portions 31 whereof somewhat dovetail section for slidable coaction with the correspondingly formed portions 32 of rectangular holes 33 through the lock member 5.

The lock member 5 is of conventional pattern excepting that it is provided with the holes 32, 33 just described and by which it is secured to the carrier 3, through application of the part 33 over the lock projections 30, and is adapted for sliding movement toward the right-hand of Fig. I to bring the portions 32 into engagement below the lock projection dovetail portions 31, in an obvious manner.

Conveniently hinged at 34 to one end of the razor head 2 is a guard or protective shield 6 having cut-outs 35, Fig. IV, for engagement with end projections 36, on said head; and a snap catch 37 remote from the hinge 34 for engagement with a cut-out or notch 38, Figs. I and VII, to lock the guard 5 in position when the razor is assembled for use. Arcuate slots 39 are also, preferably, provided in the end portions of the guard or shield 6 to accommodate blades 4 having end extensions that might otherwise interfere with the free reciprocation of the carrier 3.

Having disclosed the structural features of the improved safety razor of this invention, its use will be apparent from Fig. VIII, wherein it is noticeable that said razor is held in the one hand by the handle 1 with the tip of the forefinger or digit of the right or left hand engaging the manipulator 10, or approximately in the same position where users of safety razors place said forefinger during the prevailing act of shaving to exert pressure during the time the arm is performing a shaving stroke. This cooperative functioning of the finger and arm would be very awkward and unnatural if said finger should be constantly exerting pressure and would be out of harmony with and contrary to the natural arm movements when shaving. By locating the manipulator 10 as set forth, the forefinger functions in perfect harmony with the arm and moves one-half inch or more rearward of the handle 1 in the direction the arm is moving while performing each shaving stroke. Thus with the improved safety razor of this invention, and without any additional effort, the movements of the arm and forefinger effect a repetitive back-and-forth

movement of the carrier 3 and blade 4 during each shaving movement of the user's arm.

The blade supporting ribs 29 extending the full length of the carrier 3 permit only a comparatively small portion of the blade surface to contact the underside of the lock member 5, thereby eliminating all possible danger of the blade 4 becoming metal bound, as readily understandable from Figs. II and III, more particularly: and wherein it will be seen that the top surfaces of the projections 17 are slightly hollowed out longitudinally to define parallel edges 17', Fig. VII, the outer ones of which serve as line supports for the blade 4. It is also to be seen that the longitudinal edges 5' of the lock member 5 impinge the blade 4 outwardly of the carrier edges 17', whereby the blade's flexibility is retained, and said blade is afforded the needful degree of resiliency while being secured in a position that ensures operating rigidity. In other words, when a flexible razor blade is clamped tight between two heavier and inflexible pieces of metal it restricts the blade's flexibility to the extent of creating an obstinate and stubborn influence which has a disturbing effect upon the cutting edge of said blade. Or the edge of a conventional safety razor blade is "metal-bound" and has no flexibility corresponding to the cutting edge of a straight razor which passes over all unevennesses with a distinctive and particular sound easily discerned by the user. By provision of what I term as the twin supports 17', 29, the just noted objection is obviated, since by regulating proper adjustment of the lock member 5, the ribs 29 are slightly raised sufficiently to allow parallel clearances between the blade 4 and said lock member. Thus the edges of the center slot in the blade 4 are afforded a small degree of upward spring, and upon engaging the underside of the lock member 5 as it is moved inward relative to the head 2, accommodate sliding of the blade 4 into interlocking engagement with the projection dovetail portions 31 so as to secure said blade in operating position. It will now be apparent that the edges of the blade center slot will also be pressed inwards and the spring effect produced will serve to maintain the lock member 5 in its proper adjusted position, such cooperative functioning being obviously set up by the parts 29, 17', whereby the blade edge flexibility is not disturbed. In other words, by clamping the blade 4 upon the narrow ribs 29 and edges 17', the blade cutting edges are afforded a minute degree of oscillatory movement in use. Again, the parallel edges 5' of the lock member 5 projecting and being effective beyond the head outer edges 17', impart the requisite leverage to maintain the cutting edges of the blade 4 in such position relative to the head teeth or combs 13 that lather or the hair removed by shaving are positively prevented from working inwardly of the edges 17'. The induced spring imparted to the blade also exerts a lift upon the blade carrier 3 as indicated by the clearances 40 below said carrier and the rib 25 in Figs. II and III, which practically means the load of said carrier is transferred to those parts of the blade where the latter rests on the edges 17'. Thus the blade carrier 3 is practically placed in suspension and supported by the projections 30 engaged in the lock member 5; hence the weight of the suspended carrier 3 during reciprocation of the blade 4 will serve to steady the reciprocative motions with additional force and accuracy, reduce friction of the moving parts, and positively ensure an easy and smooth cutting position for the blade edges.

Furthermore, particular attention is also directed to the fact that the longitudinal edges of the guard 6 rest on the lock member 5 and are the same distance away from the longitudinal edges of said lock member, as the edge of the latter outwardly overlaps the head projection or blade bearing edges 17'. In other words, the longitudinal edges of the guard 6 are preferably the same distance apart as the parallel head projections 17', and the former are adjusted in use to be directly over or "plumb" with respect to the latter. In addition, the guard 6 is securely attached to the head 2 and accurately stabilized and rigidly held by the projections 36 and cut-outs 35, whereas the blade carrier 3 and blade 4 are accurately adjusted for free reciprocation relative to the parts aforesaid, as hereinbefore set forth.

From the foregoing disclosure, it is thought the invention will be well understood and its advantages appreciated, and while the description is necessarily of a detailed nature in order to clarify the invention, it is to be expressly understood that structural changes and variations may be resorted to without departing from the spirit and scope of said invention as more tersely expressed in the following claims.

Having thus described my invention, I claim:

1. A safety-razor comprising a handle with a stationary head, said head embodying a guideway and paralleling ridge projections, a carrier movable in the guideway and embodying spaced ribs with intervening projections, a flexible blade supported by the carrier ribs, and a lock member slidably engageable with the carrier projections and concurrently flexing the blade into line contact with said carrier ribs and the stationary head ridge projections. 10
2. A safety-razor comprising a handle with a stationary head, said head embodying a guideway and paralleling ridge projections, a carrier movable in the guideway and embodying spaced ribs with intervening projections, a flexible blade supported by the carrier ribs, and a lock member slidably engageable with the carrier projections and concurrently flexing the blade into line contact with said carrier ribs and the stationary head ridge projections, whereby the razor blade is rigidly secured in operative position with the cutting edges maintained flexible. 15
3. A safety-razor comprising a holder with a fixed head, a carrier movable relative to said head, a flexible blade sustained by the carrier, a member for securing the blade to the carrier by reactive force induced when said securing member is applied, means whereby the carrier is reciprocable, and a protective member overlapping the securing member and blade, said protective member coating with the blade securing member to positively prevent ingress of shaving medium or residue to the movable carrier. 20
4. A safety-razor comprising a handle with a fixed head, said head having a central guideway with paralleling ridge projections, a carrier slidably in said guideway and embodying parallel ribs with spaced projections, a flexible blade sustained by the carrier, a blade securing member adapted to interengage the carrier projections and lock the blade rigidly in line contact with said carrier projections and the fixed head ridges, and means whereby the carrier is reciprocable. 25
5. A safety-razor comprising a handle with a fixed head, said head having a central guideway with paralleling ridge projections, a carrier slid- able in said guideway and embodying parallel ribs with spaced projections, a flexible blade sustained by the carrier, a blade securing member adapted to interengage the carrier projections and lock the blade rigidly in line contact with said carrier projections and the fixed head ridges, 30
6. A safety-razor comprising a handle with a fixed head, said head having a central guideway with paralleling ridge projections, a carrier slidably in said guideway and embodying parallel ribs with spaced projections, a flexible blade sustained by the carrier, a blade securing member adapted to interengage the carrier projections and lock the blade rigidly in line contact with said carrier projections and the fixed head ridges, a rotatable cam and coercive rocker whereby the carrier can be reciprocated, and a hinged guard substantially 35 closing-in the blade securing member and said carrier. 5
7. A safety-razor as defined in claim 6 wherein the fixed head guideway is of suitable cross-section flanked by paralleling ridges, and the blade carrier is of complemental cross-section with longitudinal blade supporting ribs and intervening lock projections. 20
8. A safety-razor as defined in claim 6 wherein the fixed head guideway is of outwardly-convergent cross-section with a central groove, said guideway being flanked by parallel ridges, the blade carrier is of complemental cross-section with a rib engaging in the guideway groove, and said carrier is adapted for slight outward lift 35 relative to the fixed head, for the purpose set forth. 30
9. A safety-razor as defined in claim 6 wherein the fixed head guideway is of outwardly convergent cross-section flanked by paralleling 40 ridges, the blade carrier is of complemental cross-section with longitudinal blade supporting ribs and intervening lock projections, and said lock projections are of dovetail formation for interengagement with corresponding portions of rectangular apertures through the blade securing member. 45
10. A safety-razor as defined in claim 6 wherein the carrier reciprocating means comprises a rotary cam journaled in the razor handle, and a Y-rocker also pivoted in said handle with its leg operatively engaging said carrier. 50
11. A safety-razor as defined in claim 6 wherein the carrier reciprocating means comprises a rotary disc having an annular cam path on each face, said cam paths including equally spaced rises and the rises of the one path being staggeringly related to those of the other path, and an inverted Y-rocker also pivoted in the razor handle with its leg engaging an aperture through 55 the carrier and its fork arms ball-ended for co-action with the cam paths. 60
12. A safety-razor as defined in claim 6 wherein the guard is hinged transversely to one end of the fixed head and embodies a snap catch for co-action with the other end of said head, cut-outs are provided at both ends of the guard for engagement with complemental projections at the head ends to prevent relative lateral movement, and said guard ends have arcuate slots there- 70 through, for the purpose set forth. 65
